CLAIM

The ornamental design for a heart-shaped box, as shown and described.

DESCRIPTION

FIG. 1 is a perspective view from the front and side of a heart-shaped box of the present design, in a closed position; FIG. 2 is a top view of the heart-shaped box of FIG. 1, in a closed position;

FIG. 3 is a side view of the heart-shaped box of FIG. 1, in a closed position;

FIG. 4 is a side view of the heart-shaped box of FIG. 1, in a closed position;

FIG. 5 is a front view of the heart-shaped box of FIG. 1, in a closed position;

FIG. 6 is a rear view of the heart-shaped box of FIG. 1, in a closed position;

FIG. 7 is a bottom view of the heart-shaped box of FIG. 1, in a closed position;

FIG. 8 is a perspective view from the front and side of the heart-shaped box of FIG. 1, in a partially open position; and, FIG. 9 is a perspective view from the top and front of the heart-shaped box of FIG. 1, in an open position.
